HAIR DRIER

Robert Valverde, New York, N. Y.

Application April 22, 1941, Serial No. 389,702

10 Claims. (Cl. 34—50)

This invention relates to apparatus for drying hair, and especially to hair drying apparatus suitable for use in beauty parlors for drying women's hair without disturbing a wave set.

It is an object of the invention to provide improved equipment for drying hair, and more particular objects of the invention are to dry hair in a shorter period and at a lower temperature than heretofore, and to do it without discomfort, even in warm, humid weather.

The invention comprises a number of hollow two-chambered pads conforming to part or all of the head, the inner side of each pad carrying short, thin, pointed projections, which act to separate the wet hair and permit orifices at the base of each projection to blow a jet of dried air directly to the scalp. These projections may be tubes, pointed and open at the end that touches the scalp. The tubes are in two sets distributed among each other, each set terminating in a separate chamber in the pad. The pads are worked gently against the wet hair so as not to disarrange the coiffure, until the orifice tubes touch the scalp. Because of their number, no one pointed tube presses against the scalp with sufficient force to be annoying. Since the wet hair is mostly horizontal with the scalp and is about $\frac{1}{8}$ inch thick, very small penetration is needed.

Dry air supplied under pressure to the pressure chamber in the pad penetrates to the scalp, absorbs moisture as it passes between the horizontal hairs and is picked up by the adjacent suction tubes leading to the vacuum chamber, and goes on through the suction tube line to the air conditioning machine.

This machine is a combination of structure used in air conditioning machines and vacuum cleaners, with a sump tank to catch the precipitated moisture that passes through a vacuum valve, and a thermally-controlled by-pass around the warm motor-compressor where heat is added to the cooled air, and the air, which is dry and may be at skin temperature, is forced through a pressure tube to the pressure chambers in the pads to start a new drying cycle.

In the accompanying drawing, forming a part hereof:

Fig. 1 is a schematic drawing of the sectional pads on the hair and the special air conditioning machine.

Fig. 2 is an enlarged sectional view of one of the pads of Fig. 1 showing the distribution of the projections and their penetration to the scalp.

Fig. 3 is an enlarged detail sectional view of a portion of the structure shown in Fig. 2.

Fig. 4 is a sectional view on the line 4—4 of Fig. 3, showing distribution of hair tubes.

Fig. 5 is a perspective view showing a modified form of tube for projection into the hair.

Hollow pads 1 and 2 of Fig. 1, designed to approximately fit over portions of the scalp 3, are provided with inlet tubes 4 and 6 and outlet tubes 5 and 7, connected by air lines, comprising tubes 8 and 9, to an air conditioning machine 10. The machine 10 is a refrigerator with cooling coil 11, motor 12, compressor 13, and condenser 13' located adjacent the compressor. The motor 12

15 also drives a turbine-type fan 14 through a speed changer 15 to put the air under pressure in tube 8 and under partial vacuum in tube 9.

Moist air from the hair 16, Figs. 2 and 3, of scalp 3 is drawn through tube 9 (Fig. 1) past the 20 refrigerator coils 11, where it is cooled below its dewpoint to precipitate most of its moisture, and then through the fan 14 where centrifugal force precipitates residual moisture. The cool dried air is compressed and driven through the pressure 25 head 17 to the proportioning valve 18 operated by the adjustable thermostat 19 through the link 30. Part of the air goes through the by-pass 20 and the balance past the warm housing of the motor 12, compressor 13, and condenser 13', 30 where the relative humidity is further reduced by the addition of heat. This heated air mixes with the by-passed air at outlet 21 to bring the reconditioned air up to skin temperature or over, to avoid a chilling sensation.

35 Each time the drier is stopped, a vacuum valve 22 and breather 23 permits the accumulated moisture to flow into the sump tank 24.

The pressures, negative and positive, in air lines 3 and 9 are controlled by the shunt valve 25.

40 A cross-section of a pad is shown in Fig. 2. The concave side of pad 1 is covered with pressure tubes 26 and suction tubes 27 so distributed that a suction tube is always adjacent to a pressure tube. Since the depth of wet hair on a 45 scalp is only about $\frac{1}{8}$ inch, these tubes are short and slender. The tubes are pointed with a diagonal cut which may extend for the full free length of the tube. The tubes serve the double purpose of separating the wet air 16 (Fig. 3) and guiding the jets of dried air to the scalp 3 before spreading out through the hair and into suction tubes 27. The pad 1 is divided into two compartments 28 and 29, into which the tubes 26 and 27, respectively, open.

55 The pads 1 and 2 are concave sections having

the general contour of the head, and the tubes 26 and 27 are carefully worked into the wet hair 16 without disarranging the coiffure. The pads 1 and 2 are flexibly connected together by lacing or adjusted on a common bracket to hold them in place. Initially, machine 10 is run a while to warm up, then tubes 8 and 9 and jumper tubes 6 and 7 are connected to pads 1 and 2. These tubes 4, 5, 6, 7, 8 and 9 may be molded together in pairs or one inside the other in pairs so that one motion joins the tubes to the pads.

The dried air near skin temperature, or enough above skin temperature so that the evaporation of moisture does not produce a chilling sensation, thus reaches the scalp through pressure tubes 26 and spreads out through the hair 16, absorbing moisture. Suction tubes 27 draw in the moisture and the moisture-laden air, all of which is drawn into the machine 10 to be conditioned for further use.

Fig. 5 shows a modified construction of the tubes that project into the hair. Tubes 31 are of tapered cross-section with their side walls converging to a point. The sides of these tubes 31 are slotted, preferably for the full free length of the tubes, and the slots are of decreasing width as they approach the pointed ends of the tubes. Within the pad the tubes 31 are the same as the construction shown in Fig. 3.

Though attempted before, I believe my invention is the first to apply jets of air directly to the scalp and sideways through the hair to dry it in the quickest possible manner. While the drawing shows only two pads covering most of the scalp, this reduced number is for the sake of simplicity in the drawing. Because of the difference in the shapes of different peoples' heads, it is advantageous that the drier include a number of relatively small pads which can be hinged together to obtain the flexibility necessary to conform to heads of different size and shape. The invention is not limited to the embodiment illustrated, and various changes and modifications can be made without departing from the invention as defined in the claims.

I claim:

1. A hair drier comprising a pad, a partition within the pad dividing said pad into a pressure and a suction chamber, a plurality of small diameter tubes connected with the pad, alternate tubes communicating with the respective chambers, all of said tubes extending from a common face of the pad for insertion through the hair and against the scalp of a wearer, a suction line connected with the suction chamber, a pressure line connected with the pressure chamber, and an air conditioning unit including a housing having an inlet and an outlet to which the suction and pressure lines respectively are connected, a refrigerating coil at the inlet end of the housing into which air comes from said suction line, a fan for drawing the air over the coil, a compressor, a motor between the fan and compressor with driving connections to said fan and compressor, the motor and compressor being in the housing and in the air stream from said fan so that they heat the air, a by-pass conduit that terminates adjacent the housing outlet and through which air from the fan can flow around the motor and compressor, a valve for controlling the proportion of air that flows through the by-pass, and thermal-responsive means exposed to the warm air near the outlet end of the housing for operating said valve.

2. Hair drying equipment including a hollow

body that rests on the head of the person whose hair is to be dried, said body comprising a scalp-conforming, hollow pad having a plurality of sections and means for adjusting the sections with respect to one another to fit the head of the wearer, partition means dividing the pad into air-supply and exhaust chambers, conduits extending downward from the respective chambers and opening through the concave side of the pad, the outlet ends of the conduits from the respective chambers being adjacent one another and in contact with the hair when the pad is in operative position so that with the air currents from and to the respective conduits penetrating moist hair to the scalp cross currents of air are circulated through the hair, air conditioning apparatus connected with the hollow body including tubing through which moisture-laden air is withdrawn from the suction chamber, a housing with an inlet to which said tubing is connected, a cooling surface in the housing in the path of air passing through the housing, a refrigerating system for circulating a cooling medium behind the cooling surface to chill said cooling surface below the dew point of the air supplied to the housing, other passages through which air from the cooling surface housing is delivered to the pressure chamber of said hollow body, a fan for moving the air and increasing the pressure of the air as it moves toward the pressure chamber, heating means in one of the passages and downstream from the cooling apparatus for raising the temperature of the air to reduce its relative humidity, and means for controlling the extent of the reheating.

3. A hair drier comprising a pad, a partition within the pad dividing said pad into a pressure and a suction chamber, a plurality of small diameter tubes connected with the pad, alternate tubes communicating with the respective chambers, all of said tubes extending from a common face of the pad for insertion through the hair and against the scalp of a wearer, a suction line connected with the suction chamber, and a pressure line connected with the pressure chamber.

4. A hair drier including a plurality of small tubes that extend into the hair and against the scalp, an air line, a chamber connecting the air-line with some of the tubes and through which air is supplied to dry the hair, a suction line, a chamber connecting the suction line with others of said tubes for withdrawing moist air from the vicinity of the hair, means for circulating and conditioning the air including a container communicating at one end with the pressure line and at the other end with the suction line, a drain outlet at the bottom of the container, a sump tank below the drain outlet, a vacuum valve commanding the drain outlet, apparatus in the container including a cooling coil, a fan, a reduction gear unit, a motor, and a compressor positioned in the order named between the suction and pressure end of the container, and a by-pass around the motor and compressor for the passage of cool air from the vicinity of the cooling coil to the pressure end of the container.

5. Hair drying apparatus including a head cover made up of a number of hollow pads, each with a plurality of small pointed tubes extending from one face of the pad and connected to the pad at their larger ends, a partition within the pad, substantially parallel with the face of the pad from which the tubes extend and dividing the interior of the pad into two chambers, one-half of the tubes opening into the chamber im-

mediately behind said face, and the other half passing through this first chamber and opening into the chamber beyond said partition, all of said tubes having orifices at their pointed ends for the circulation of air into and out of said tubes, a conduit communicating with one of the chambers for supplying air to that chamber under pressure, and another conduit communicating with the other chamber for withdrawing air and creating a suction in the tubes communicating with that chamber.

6. A hollow pad with one face covered with pointed pressure tubes for introducing numerous jets of dried air directly to the scalp for the purpose of quickly and comfortably drying wet hair, other pointed suction tubes distributed among the pressure tubes to draw these jets of air and moisture away from the hair, and a partition generally parallel to said face of the pad and dividing the interior of the pad into a pressure and a suction chamber, said pressure and suction tubes being connected with the respective chambers, said pressure chamber having an inlet for the drying air and said suction chamber having an outlet for the moisture-laden air.

7. Hair drying apparatus comprising a plurality of hollow pads with bottom faces shaped to the general contour of a head and joined together by lacing that serves as a hinged connection, each of said pads being provided with an inlet through which air enters the hollow pad, a plurality of closely spaced, small pointed tubes extending from the bottom face of each pad and connected with the pad at their larger ends, said tubes having orifices at their pointed ends for discharging a plurality of air streams into spaced regions under the hair and close to the scalp.

8. A hair drier comprising a set of hollow pads conforming to at least a part of the scalp, partition means dividing each pad into air-supply and exhaust chambers, the air supply chamber having an inlet for air and the exhaust chamber having an exhaust outlet, tubular fingers on the concave sides of the pads serving as orifices to the pads and extending downward from the respective chambers to supply air to and exhaust it from the hair and scalp.

9. A hair drier including a scalp-conforming, hollow pad, partition means dividing the pad into air-supply and exhaust chambers, an inlet to the air pressure chamber, an outlet from the exhaust chamber, hollow tubes extending downward from the respective chambers and projecting from the concave side of the pad, the open ends of the tubes from the respective chambers being adjacent one another so that with the tubes penetrating moist hair to the scalp cross currents of air are circulated through the hair.

10. A hair drier comprising a scalp-conforming hollow pad, a partition dividing said pad into pressure and suction chambers, a plurality of pressure fingers extending from one face of the pad and communicating with one chamber of the pad, a plurality of suction fingers extending from said face of the pad and communicating with another chamber of the pad, apparatus for drying, tempering and circulating air comprising in combination a housing having an inlet and an outlet through which air passes, a conduit connecting the suction chamber of the pad with the inlet of the housing, another conduit connecting the pressure chamber of the pad with the outlet of the housing, a refrigerator compressor and cooling coil located in said housing, a turbine-type fan for moving the air through the housing, a motor for operating the refrigerator compressor and the fan, a sump tank at the bottom of the housing, a vacuum valve for controlling communication between the sump tank and the housing, a by-pass through which a portion of the air flows after being dried first on the cooling coil and then by centrifugal force in the fan while other of the air is heated in the housing by passage over the motor and compressor, a proportioning valve for determining what portion of the air travels through the by-pass, a thermally-responsive operator for the proportioning valve, and a conduit in which the heated air mixes with the air from the by-pass and tempers the air from the by-pass as the air is forced back to the pressure fingers.
